UNITED STATES PATENT OFFICE.

WILLIAM FRANCIS CROWE, OF LOS ANGELES, CALIFORNIA.

DRYING MECHANISM.

1,187,715.

Specification of Letters Patent. Patented June 20, 1916.

Application filed September 7, 1915. Serial No. 49,329.

To all whom it may concern:

Be it known that I, WILLIAM FRANCIS CROWE, a citizen of the United States, residing at Los Angeles, in the county of Los Angeles and State of California, have invented new and useful Improvements in Drying Mechanisms, of which the following is a specification.

This invention relates to improvements in drying mechanisms, particularly to the class and description generally employed in the manufacture of cans to be used for the preservation of various foodstuffs.

The primary object of my invention is the provision of an improved, economical and sanitary drier, which is adapted to dry the can parts that have had, previously applied, a coating of sealing compound, or to remove any moisture said can parts may have come in contact with.

Another object of the invention is to provide an improved drier of the nature stated, that is small and compact of formation, taking up a minimum of floor space, that is positive in operation and simple in construction.

Another object resides in the provision of an improved drier of the character stated, which comprises a series of horizontally extending rotating disks, so arranged within a suitable chamber, with suitable transfer means, in connection with said disk series, to transfer the can parts from one disk to another disk of said disk series in the presence of any suitable heating medium and finally discharged out of the casing or chamber.

With the above and other objects in view the invention further consists in the new and novel provision, formation, construction, combination, organization, and relative arrangement of parts, members and features, all as hereinafter more fully described, shown in the drawings and particularly pointed out in the appended claims, it being understood that, I do not desire to limit myself to the specific provision, formation, construction, organization, and relative arrangement of parts, members and features herein shown and described, but reserve the right to vary the same within the spirit of the invention and without sacrificing any of the advantages thereof and within the terms of the appended claims.

In the drawings: Figure 1 is a top plan view of a machine constructed in accordance

with the invention, the central part of the cover B, of the machine being torn away to permit a clearer view of the working parts and also to avoid a confusion of dotted lines. 60 Fig. 2 is a cross-sectional view taken on the line X²—X² of Fig. 1 and looking in the direction of the appended arrows, part of the casing on left side being shown to permit a view of the supporting column F, of 65 which there are four, as indicated in Fig. 1. Fig. 3 is a cross-sectional view of the invention, taken on the line X³ of Fig. 1 and looking in the direction of the appended arrows disclosing the relative positions of 70 the rakes and chutes, certain parts being torn away to permit a clearer view of the rakes and chutes. Fig. 4 is a fragmentary top plan view to an enlarged scale of certain of the parts, and particularly the rakes, 75 shown in the several views of the drawings. Fig. 5 is a side elevation of the same parts taken on the line X⁵ of Fig. 4 and looking in the direction of the appended arrows. Fig. 6 is a top plan view of one of the several 80 chutes employed in the invention. Fig. 7 is a side elevation of the same part.

Like parts and combinations of parts are designated by like characters of reference throughout the several views of the drawings. 85

Referring to the drawings, the letter A designates a supporting table, for the mechanism of any suitable construction, which may be supported in any suitable manner, in 90 this instance by the legs —a—. Secured to the underside of the table A is the bearing O bolted as at 22 to the table A, which provides one of the bearings for the support of the driven shaft J. The other bearing required for the support of the shaft J is cast within the table itself as shown at 95 —f—. The driven shaft J is provided on its outer end with a tight and loose pulley M or any other suitable means by which power 100 may be transmitted to the machine. On the upper surface of the table A is mounted a drum, comprising the parts I and C, which is mounted for rotation through the medium of an extension —c— on the under side 105 of the disk I, journaled in the table A as at —p—, said extension —c— being supplied with a suitable beveled gear G, keyed or otherwise fastened, as at 23, adapted to mesh with a beveled gear N, which is keyed 110 or otherwise secured to the driven shaft J.

The drum CI is provided with a sta-

tionary cover B, which is securely mounted on the columns F by the lugs —e— and the bolts 11, said columns F being secured, on their lowermost ends to the table A by means 5 of the bolts 12. Within the drum CI is mounted a set of horizontally extending disks D, each disk being securely mounted on the wall C, of said drum CI by means of the lugs 32 and the rivets 10. Each of the 10 disks D is provided with an aperture in the center to permit the entrance of other mechanical means employed to make the machine complete, which will be hereinafter described.

15 Two supporting brackets —h— and —j— are hung from the cover B and bolted as at 15 and 17 respectively, the lower end of —h— projecting through the aperture in the extension —c— and then bent upwardly 20 and bolted to the under side of the table A as at 16.

The rakes as shown in several views of the drawings consist mainly of two sections, a movable section K, which comprises the 25 stud 28 riveted thereto as at 30, and a stationary section, which comprises the straps —k— with the studs 29 mounted thereon as shown in Figs. 4 and 5 of the drawings.

To the bracket —j— is secured a series 30 or set of brackets —i—, one of said brackets —i—, for each one of said disks D. One rake is supplied to each and every one of the brackets —i—, the stationary section of said rake being riveted to the bracket —i— as at 31. The bracket —i— contains an aperture 33, through which the stud 28 is entered and allowed to oscillate upwardly and downwardly freely in the event of any 35 irregularities on the upper face of the disk D while the lower edge of the movable section K is in contact with the said upper face of disk D. The studs 29 merely act as 40 guards for the rake K to keep it in position. The brackets —i— are fastened to the bracket —j— by rivets as at 19.

Each disk D and rake K is provided with 45 a chute L with an upstanding side 25, except the lowermost disk which is supplied with a chute E with upstanding sides 24. The chutes L are held in position by their 50 upstanding sides being riveted to the brackets —h— and —j— as at 20 and 18 respectively. The chute E is held in position by one of its upstanding sides being riveted 55 to the bracket —j— as at 18.

A guiding band —g— is provided for each disk which extends from the bracket —h— to the bracket —j— along the inner edge of each disk D, and secured to the brackets 60 —h— and —j— respectively by the rivets 21 and 18.

The heating means H comprises the steam coils, as shown in several views of the drawings, with an intake 26 and an exhaust 27, 65 ranging within the drum CI.

The cover B is supplied with a feed opening —d— as shown in Figs. 1 and 3 and also an opening is provided in the center of the disk I of the drum CI for the discharge of the can-parts treated and handled by the 70 machine, thereby supplying a chamber that is practically air tight, except for the above mentioned apertures, and adapted to 75 serve the heating units supplied by the coils H for a greater length of time.

The heating means H may be of any desired arrangement of steam or electric coils or preheated air means may be employed, any one of which may be substituted for the other if so desired.

The machine having been set in operation, the can parts, to be dried, after a sealing compound has been applied thereto, or for the purpose of removing moisture therefrom to prevent rust, are fed, by hand or otherwise, through the feed opening —d— onto the uppermost disk D. The guiding band —g— within the inner edge of the disk D serves as a guard to prevent the can parts from dropping over the inner edge of disk 90 D and causes the can parts to lie between the guiding band —g— and the annular wall C of the drum CI and on the disk D. The drum CI, through the medium of suitable transmission means, rotates toward the 95 left, thereby causing the disks D, which are secured to the annular wall C of the drum CI, by the lugs 32 and the rivets 10, to rotate toward the left also, causing the can parts to be carried around to a point where a rake 100 K is stationed and suspended from the bracket —i—, said bracket being mounted on the supporting bracket —j—. The can part by contact with the rake K is deflected 105 in its course toward the inner edge of disk D, the rake K being set at the desired angle to produce the best results in that respect. At this point a suitable chute is supplied, extending from the uppermost disk D to the disk D immediately below and fastened to 110 the brackets —h— and —j— by the rivets 20 and 18 respectively, for the purpose of conveying the can parts from one to the other of said disks, said chutes being placed at the desired incline to produce the required results. This feed of the can parts continues in the same manner over each and all of the disks D until the can part reaches the lowermost disk D of the set, where they are deflected by the rake means K, off of 115 said lowermost disk and into the chute E, which is fastened to the supporting bracket —j— as at 18, for conveying the can parts from the machine, said chute projecting through the aperture formed in the center 120 of the machine for that purpose and clearly shown in Figs. 2 and 3 of the drawings. Suitable receptacles being provided for the can parts when dried.

The can parts as herein used in this ap- 130

plication of the invention, designate the ends, in or on which a sealing compound has been applied, or have come in contact with moisture liable to cause rust, which 5 must necessarily be dried so that the can parts may be neatly and compactly stored until further use of said can parts is desired. The can parts may also designate the can body with one or both ends attached which 10 frequently have to be dried, it simply being necessary that the disks be spaced one above the other the proper pre-determined distance.

Having thus fully described my invention, what I claim and desire to secure by Letters Patent, is:

1. A can-part drying machine comprising a chamber; a set of rotatable disks, provided with centrally located apertures, in said 20 chamber; means for rotating said disks and rakes in contact with said disks.

2. A can-part drying machine comprising a chamber; a set of rotatable disks, supplied with central apertures, in said chamber; 25 means for rotating said disks; rakes in contact with said disks and suitable chutes in connection with said rakes.

3. A can-part drying machine comprising a chamber; a set of rotatable disks, provided 30 with an aperture formed in the center of each of said disks, in said chamber; transmission means for rotating the disks; rakes in contact with said disks; and suitable chutes adjacent said rakes for conveying the 35 can-parts from one to the other of said disks.

4. A can-part drying machine comprising a chamber; a set of rotatable disks, with an 40 aperture extending vertically through said set, mounted in said chamber; transmission means for rotating said disks; a rake in contact with each of said disks; a chute for each of said disks and adjacent each of said rakes for depositing the can-parts on various 45 of the disks; and a chute for conveying the can-parts from the lowermost of said disks and without the chamber.

5. A can-part drying machine comprising a chamber; a set of rotatable disks, provided 50 with apertures to permit the transfer of articles to the various disks, mounted in said chamber; transmission means for rotating said disks; a rake in contact with each of said disks; a chute for each of said disks and adjacent each of said rakes, for depositing the can-parts on various of the disks; a chute for conveying the can-parts from the lowermost of said disks and without the chamber; and means for heating the interior 55 of said chamber.

6. A can-part drying machine comprising a chamber; a set of rotatable disks, provided

with an aperture extending vertically and centrally through said set to permit the transfer of articles from one to the other of 65 said disks, mounted in said chamber; a rake in contact with each of said disks; transmission means for rotating said disks; a chute for each of said disks and adjacent each of said rakes for depositing the can-parts on various of the disks; a chute for conveying the can-parts from the lowermost of said disks and without the chamber; means for heating the interior of said chamber; and a supporting table. 75

7. A can-part drying machine comprising a chamber; a set of rotatable disks, provided with centrally located apertures to permit the discharge of articles from said disks, mounted in said chamber; transmission means for rotating said disks; means to transfer articles from one disk to the other and ultimately from the chamber; means for heating the interior of said chamber; and a supporting table. 80

8. A can-part drying machine comprising a revolving chamber; a set of disks mounted in and carried by said chamber; transmission means for rotating said chamber; means to transfer articles from one disk to the other and ultimately from the chamber; means for heating the interior of said chamber; and a supporting table on which said chamber is mounted. 85

9. A drying machine comprising a revolving chamber; a set of disks mounted in and carried by said chamber; transmission means for rotating said chamber; a rake in contact with each of said disks; a chute for each of said disks and adjacent each of said rakes 90 for depositing the can-parts on various of the disks; a chute for conveying the can-parts from the lowermost of said disks and without the chamber; and means for heating the interior of said chamber. 95

10. A drying machine comprising a revolving chamber; a set of disks mounted in and carried by said chamber; means for rotating said chamber; a rake in contact with each of said disks; a chute for each of said disks and adjacent each of said rakes for depositing the can-parts on each of the disks; a chute for conveying the can-parts from the lowermost of said disks and without the chamber; means for heating the interior of 110 the chamber; and a table adapted to provide a support for said chamber and a bearing for said chamber. 115

In testimony whereof I affix my signature in the presence of two witnesses.

WILLIAM FRANCIS CROWE.
